FIG. 3.

FIG. 4.

Inventor
MANUEL BRICHER.

By *J. Haughey, Jr.* Attorney

UNITED STATES PATENT OFFICE.

MANUEL BRICHER, OF POCATELLO, IDAHO.

WRENCH.

1,387,346.

Specification of Letters Patent.

Patented Aug. 9, 1921.

Application filed January 11, 1921. Serial No. 436,498.

To all whom it may concern:

Be it known that I, MANUEL BRICHER, a citizen of Mexico, residing at Pocatello, in the county of Bannock and State of Idaho, 5 have invented certain new and useful Improvements in Wrenches; and I do hereby declare the following to be a full, clear, and exact description of the invention, such as will enable others skilled in the art to which 10 it appertains to make and use the same.

This invention relates to new and useful improvements in wrenches of the character having a stationary jaw and a movable jaw and has for its primary object the provision 15 of an actuating means for the movable jaw which will permit of a finer adjustment to be obtained of the jaws to a nut or the like over similar devices and which provides against the movable jaw slipping from the 20 nut by moving accidentally away from the stationary jaw during the use of the device.

Another object of this invention is the provision of a shank so constructed that it will firmly support both jaws and permit 25 free sliding movement of the movable jaw as well as forming a guard for the feed screw and permitting the latter to extend the full length thereof so that a wide adjustment of the movable jaw may be had.

30 A further object of this invention is the provision of a handle so constructed that it is capable of withstanding considerable strain and which will be comparatively light in weight and also when secured to the 35 shank any possibility of the same becoming accidentally detached or broken by the shank is obviated.

A further object of this invention is the provision of a connection between the handle and shank which besides forming a durable connection between said parts, will also form a support for end of the feed screw.

40 A still further object of this invention is the provision of a wrench of the above stated character, which will be simple, durable, and efficient, and which may be manufactured and sold at a comparatively low cost.

With these and other objects in view as 45 will become more apparent as the description proceeds, the invention consists in certain novel features of construction, combination, and arrangement of parts as will be hereinafter more fully described and claimed.

50 For a complete understanding of invention, reference is to be had to the following

description and accompanying drawings, in which:—

Figure 1 is a side elevation, illustrating a wrench constructed in accordance with my 60 invention,

Fig. 2 is a rear elevation partly in section illustrating the same,

Fig. 3 is a perspective view illustrating 65 the sliding jaw,

Fig. 4 is a similar view illustrating an attaching block,

Fig. 5 is a sectional view taken on the line 5—5 of Fig. 2.

Referring in detail to the drawings, the 70 numeral 1 indicates the shank having formed integrally with one end a stationary jaw 2 and attached to its other end a handle 3. The shank 1 includes spaced parallel members connected together at one of their 75 ends by the jaw 2 and have their other ends slotted longitudinally to receive the end of a handle reinforcing member or plate 5 and the latter has its side faces covered with handle forming elements 6 constructed from 80 wood or any other material suitable for the purpose so as to coöperate with the plate 5 in forming the handle 3. The handle so constructed will be capable of withstanding considerable strain and still be light in 85 weight and convenient to grasp. The handle forming elements 6 are secured to the plate 5 by rivets 7 and terminate short of the attached ends of said plate so as to expose the side faces thereof and which are engaged by portions 8 of a block 9. The portions 8 are substantially rectangular and are connected by a web 10 which is arranged

between the members 4 at their bifurcated ends and at one end is provided with a slot 95 to receive the attached end of the plate 5 and with a socket 11 at its other end, in which is secured one end of a feed screw 12. The portions 8 are provided with alined

openings to receive rivets 13 which pass 100 through the bifurcated ends of the members 4 and also the plate 5, whereby said parts are firmly secured together. The feed screw 12 lies wholly between the members 4 of the shank and has its other end secured to the 105 jaw 2.

A movable jaw 14 has an active face 15 adapted to coöperate with the active face 16 of the jaw 2 in gripping nuts or similar devices, and the body portion 17 of said jaw 110 14 is provided with a longitudinal slot 18 to receive the members 4 of the shank 1 and

also the feed screw 12. A transverse slot 19 is formed in the body portion 17 of the jaw 14 and intersects the longitudinal slot 18 and is adapted to receive an adjusting nut 20, the latter being mounted upon the feed screw 12 so that upon rotation thereof the jaw 14 will be moved on the shank 1 toward and from the jaw 2 depending upon which direction the nut is rotated. The adjusting nut 20 confined within the slot 19 and mounted upon the feed screw 12 provides a positive adjustment of the jaw 14 which will prevent said jaw from moving accidentally when applied to a nut or the like 10 consequently preventing the wrench from slipping. The adjusting screw 12 extending the full length of the shank provides a wide adjustment of the jaw 14 with respect to the jaw 2 thereby permitting the device 15 to have an extremely large range of adjustment to nuts of small sizes as well as large sizes.

An important feature of this invention is that the wrench may be held upon the nut 25 or other object to be tightened and adjusted to grip the nut or other object by one hand only.

While I have shown and described the preferred embodiment of my invention, it 30 will be understood that minor changes in construction, combination and arrangement of parts may be made without departing from the spirit and scope of the invention as claimed.

Having thus described my invention what I claim is:—

1. A wrench having a fixed jaw member provided with a shank bifurcated at its inner end, a screw associated with the shank, a 40 jaw movable on the shank, adjusting means for the movable jaw coöperating with the screw, a block having a socket to journal the screw, said block being recessed for interfitting with the shank, a handle plate extending 45 into the block and shank and fastening means common to the said shank and said plate.

2. A wrench comprising a shank including spaced parallel members, a stationary jaw formed on one of the ends of said members, said members having their other ends bifurcated, a handle forming plate secured within the bifurcated ends of said members, grip elements secured to the faces of said plates, a block overlying the bifurcated ends 55 of said members and extending between said members and having a slot in one end to receive the handle forming plate and a socket in its other end, a feed screw having one end secured in said socket and located between said members and secured to the stationary jaw, a movable jaw mounted on said members, and an adjusting nut associated with the movable jaw and mounted on the feed screw. 60

3. A wrench comprising a shank including spaced parallel members, a stationary jaw formed on one of the ends of said members, said members having their other ends bifurcated, a handle forming plate extending into the bifurcated end of said members, grips secured to the bases of said plate, a block including rectangular portions connected by a web, said rectangular portions adapted to overlie the plate and the side 75 members and have the web portion arranged between said side members and provided with a groove in one end to receive the plate and a socket in its other end, said rectangular portions having aligned openings, rivets 80 extending through said openings, bifurcated ends of said members, and the plate, a feed screw secured in the socket and to the stationary jaw, a movable jaw on said members, and an adjusting nut associated with the movable jaw and mounted on the feed screw. 85

In testimony whereof I affix my signature in presence of two witnesses.

MANUEL BRICHER.
